Christopher M. Cordley
BY
Abel L. Brownsey ATTORNEY

UNITED STATES PATENT OFFICE.

CHRISTOPHER M. CORDLEY, OF NEW YORK, N. Y.

DESIGN FOR A BEVERAGE CONTAINER.

Application filed July 7, 1926. Serial No. 18,266. Term of patent 7 years.

To all whom it may concern:

Be it known that I, CHRISTOPHER M. CORDLEY, a citizen of the United States, residing at New York, in the county and State of New York, have invented a new, original, and ornamental Design for Beverage Container, of which the following is a specification, reference being had to the accompanying drawing, forming part thereof.

The figure is a perspective view of a beverage container, showing my new design.

I claim:

The ornamental design for a beverage container, as shown.

CHRISTOPHER M. CORDLEY.
